UNITED STATES PATENT OFFICE.

OSCAR M. SHANNON, OF CHICAGO, ILLINOIS.

LAUNDRY-DRIER.

SPECIFICATION forming part of Letters Patent No. 336,758, dated February 23, 1886.

Application filed March 30, 1885. Serial No. 160,575. (No model.)

To all whom it may concern:

Be it known that I, OSCAR M. SHANNON, a resident of Chicago, in the county of Cook and State of Illinois, have invented certain new and useful Improvements in Laundry-Driers; and I do hereby declare that the following is a full, clear, and exact description thereof, reference being had to the accompanying drawings, and to the letters of reference marked thereon, which form a part of this specification.

This invention relates to that class of laundry-driers in which the drying-chamber is provided with a series of sliding gates adapted to be separately drawn out of the chamber for the purpose of placing thereon or removing therefrom the articles to be dried.

The invention more particularly concerns the air-conducting contrivances and the construction of the gates in such a drier, and has for its object to insure a more economical, efficient, and satisfactory working of the apparatus.

In the accompanying drawings, which illustrate my improvements, Figure 1 is a section of the drier transverse to the several gates therein and cutting the heater or stove which is employed in conjunction with the drying-chamber. Fig. 2 is a vertical section in the plane of the line $x-x$ of Fig. 1. Fig. 3 is a detail.

A A represent the side walls, and A' the top of the drying-chamber.

B is a stove or heater connected with the drying-chamber for the purpose of heating the air admitted to the latter.

C are the several gates provided with bars c, upon which the clothes to be dried are hung, and constructed to slide into and out of the drying-chamber.

D are sheet-metal heating-drums located in the drying-chamber below the gates C, through which drums the products of combustion from the stove are passed for the purpose of heating the air in the drying-chamber, D' being the pipe leading from said drums to the chimney.

E is a box located at the bottom of the drying-chamber, and having its upper wall perforated for the admission and distribution of

air within said drying-chamber; and F F are the flues or passages by which the air is withdrawn from the drying-chamber after it has passed upward through the clothes and taken up its quota of moisture therefrom.

It is a distinctive feature of the present invention that the outlet-flues F are constructed to deliver at some point in the passage which conducts away the products of combustion from the stove, thereby utilizing the chimney-flue and insuring an active circulation of air through the drier.

The stove B, as it is shown in the present drawings, consists of a fire-box, B', a surrounding water-back, b, and an ash-pit, b'. The top plate, B², of the stove extends back far enough to support the masonry, which is generally laid with its front face flush with the back plate, b², of the stove. A broad and relatively shallow flue, b³, leads from the fire-space rearwardly and communicates with the drum D, as shown distinctly in Fig. 1. A smaller passage, b⁴, leads from the open space beneath the stove to the air-distributing box E, the stove being supported on legs or otherwise constructed to admit air from the exterior of the stove to said box E, as also shown in said Fig. 1.

B³ is a vertical flue located centrally at the back of the stove, and preferably having its walls cast integral with the back plate of the stove, said flue B³ being constructed to receive the air from the outlet-air-flues F at f and communicating with the passage b³ at b⁵. Within the passage B³, and between the inlet-opening f and the discharge-opening b⁵ thereof, is located a damper, b⁶, by which the said passage may be wholly or partially closed, as may be desired, for the purpose of regulating the circulation of air through the drying-chamber. Said damper b⁶ has a rod running off to the side of the stove with a bent end or lever in the usual form, by which it may be conveniently operated, as shown in Fig. 2.

The flues F are contrived to take the air from the top or upper region of the drying-chamber after it has passed in contact with the articles to be dried; and, in order that said flues may operate to induce a more even circulation throughout the entire extent of the

drying-chamber, I prefer to employ elevated horizontal flues F', set in or adjacent to the walls A and running along said walls in connection with the vertical flues F, said horizontal flues being provided with several apertures at different points, as more plainly shown in Fig. 2.

In the operation of the drier having its circulating-flues constructed as above set forth, 10 the air from the drying-chamber enters the current of combustion products, and the draft of the stove impels a movement of such air, which is far more active and efficient than it is when said air is discharged by an independent outlet.

For the general object last-mentioned it would be practicable to connect the air-outlet flues F with the chimney direct or with the pipe D'; but as there is sometimes a temporary back draft in the chimney and the pipe D', resulting from change in the direction of the wind or other cause, there is danger that soot will be blown into the drying-chamber through the flues F with the effect of soiling the clothes. I therefore prefer to connect the said flues F with the passage for the combustion products at the point indicated—to wit, between the heating-drum and the firebox—or at a point of the heating-drum itself, 25 for the reason that within said drum the movement of the current is slow, and the soot thus returned will naturally be deposited.

Referring next to the sliding gates, one of my improvements therein consists in providing 30 for each gate a pulley, C', or its equivalent support located at a little distance in front of the drier-wall through which the gates are drawn out, which pulley, acting in conjunction with inner guide-pulleys, sustains the 35 gate in a substantially horizontal position when drawn out, thereby dispensing with the long stationary rails which have heretofore been employed to sustain the extended gate and lessening the space occupied by the apparatus.

Another improvement relating to the gates 40 consists in providing a metal rail, C², at the top of each gate to run on the stationary pulley or support, C', substantially as shown.

The gates C are composed of the end uprights, c' c², united by the horizontal bars c, 45 said uprights being wide enough to close the opening provided in the wall A for the passage of the gate and the articles thereon when the gate is either entirely closed or entirely drawn out.

C² C³ are stationary rails or bars, which in my improved construction are limited to the interior of the drier, and are each employed only to uphold and guide the inner end of a 50 gate through the medium of the pulleys c³ c⁴ set in the mortise of the inner upright, c².

The elevated metal rail C² is attached to the uprights c' c², and at its front end is extended beyond the upright c' far enough to

reach over the pulley C' when the gate is closed. 65 By this construction the said rail resting on the pulley C' co-operates with the lowermost pulley c³ to hold the gate horizontal in its extended position.

As a desirable construction, a series of loose 70 pulleys, C', may be mounted on a rod, c⁵, the rod being supported at its ends by brackets C⁴ and upheld between its ends by hangers or pendent straps C⁶, as shown in Figs. 2 and 3.

The extent to which the brackets C⁴ project 75 in front of the adjacent wall of the drier-chamber will of course be sufficient to give the desired horizontal distance between the bearing-points c³ and C', to hold the gate practically horizontal when fully drawn out. 80

I claim as my invention—

1. In combination with a drying-chamber provided with inlet and outlet air passages and a heating-drum, a heater constructed with a passage leading from the fire-space 85 to the heating-drum, and a passage connected with the air-outlet and leading into the said passage to the drum, substantially as described.

2. The combination, with a drying-chamber provided with an air-outlet, of a heating-drum located within said chamber, and a broad air-distributing box connected with a suitable air-inlet and located below the heating-drum, and also provided with widely-distributed 95 holes in its upper inclosing-wall, whereby the air is delivered in relatively-small streams beneath various and widely-distributed portions of the heating-drum, substantially as described. 100

3. The combination, with the drying-chamber, of an air-outlet passage terminating at its receiving end in a horizontal passage, F', having several openings at different parts of the drying-chamber, substantially as and for the 105 purpose set forth.

4. The combination, with a drying-chamber provided with a heating-drum and an air-outlet pipe, of a heater provided with a passage, b³, leading to the heating-drum, and a 110 passage, B³, connected with the air-outlet of the drier and opening into the passage b³, and also provided with a damper, b⁶, substantially as and for the purpose set forth.

5. A sliding drier-gate provided with a rail 115 extended beyond the front end of the gate, in combination with a stationary pulley supported in front of the drier, and a support arranged within the drier to receive upward pressure from the inner end of the gate, substantially as described.

6. In combination with the drying-chamber having a fixed interior rail and an external pulley, C', supported in front of the drier, a sliding gate provided with pulleys c³ c⁴, running on said inner rail, and an elevated rail, C², running on the exterior pulley, substantially as described. 125

7. In combination with the wall of the dry-
ing-chamber and a series of sliding gates each
provided with a top rail extending beyond
the front end of the gate, a rod supported by
5 brackets C⁴, and a series of loose pulleys on
said rod to receive the said top rails, substan-
tially as described.

In testimony that I claim the foregoing as
my invention I affix my signature in presence
of two witnesses.

OSCAR M. SHANNON.
